(57) **ABSTRACT**

A multi-point calibration method for the depth of a horizontal directional drilling guiding instrument comprises: maintaining a constant power output of a normal power transmitter in a specific power supply condition; selecting at least two depth calibrations; receiving a signal transmitted from a transmitter and an intensity of a signal at a depth calibration position by a receiving instrument; performing a signal shaping and an analog/digital conversion to the signal received by a signal receiving instrument; and entering the signal into a central digital signal processor, and performing a depth calibration by any compensation method to obtain a required measuring depth. The invention improves the accuracy of the depth measurement of the horizontal directional drilling guiding instrument by using a plurality of compensation methods to compensate any error caused by the electric fields and environmental noises and occurred in the depth measurement of horizontal directional drilling guiding instrument.

**MULTI-POINT CALIBRATION METHOD FOR
THE DEPTH OF A HORIZONTAL
DIRECTIONAL DRILLING GUIDING
INSTRUMENT**

**CROSS REFERENCE TO RELATED
APPLICATIONS**

This application claims priority to Chinese Patent Application No. 200910130862.5, filed on Apr. 16, 2009, which is hereby incorporated by reference in its entirety.

BACKGROUND OF THE INVENTION

1. Field of the Invention

The present invention relates to a technical area of depth measurements of a guiding instrument, and more particularly to a multi-point calibration method for the depth of a horizontal directional drilling guiding instrument.

2. Description of the Related Art

At an early stage, horizontal guiding instruments apply a dipole source and two antennas to measure the depth of a probe.

$$R = d / ((s_1/s_2)^{1/3} - 1)$$

where, s_1 and s_2 are intensities of signals transmitted from a transmitter and received respectively by two detecting instruments having a one-dimensional antenna, and d is the distance between the two detecting instruments having the one-dimensional antenna. This depth measuring method usually has a relatively large depth error.

Another present existing method is a single-point calibration method that obtains a measured value M_0 , provided that the distance (k_0) is known, and the depth (r) is calculated by the following equation:

$$r = (M_0/s)^{1/3}$$

where, s is the intensity of a signal transmitted from a transmitter and received by a measuring instrument, and this method provides a more accurate depth measurement, but the range of the accurate measurement is very narrow due to other factors such as the existence of electric fields and environmental noises. The accuracy will be increasingly lower after a certain specific depth is reached. The greater the distance, the greater is the error.

SUMMARY OF THE INVENTION

Therefore, it is a primary objective of the present invention to overcome the shortcomings of the prior art including the inaccuracy and the depth limitation of the conventional measuring method by providing a multi-point calibration method for the depth of a horizontal directional drilling guiding instrument.

To achieve the foregoing objective, the present invention provides a multi-point calibration method for the depth of a horizontal directional drilling guiding instrument, and the method comprises the steps of:

(1) maintaining a constant power output of a normal power transmitter in a specific power supply condition;

(2) selecting at least two depth calibrations;

(3) receiving a signal transmitted from a transmitter and an intensity of a signal at a depth calibration position by a receiving instrument;

(4) performing a signal shaping and an analog/digital conversion to the signal received by a signal receiving instrument; and

2

(5) entering the signal into a central digital signal processor, and performing a depth calibration by any compensation method to obtain a required measuring depth.

The invention has the advantage of improving the accuracy of the depth measurement of a horizontal directional drilling guiding instrument by using compensation methods to compensate an error caused by the electric fields and environmental noises and occurred in the depth measurement of the horizontal directional drilling guiding instrument.

BRIEF DESCRIPTION OF THE DRAWING

FIG. 1 is a block diagram of a receiving instrument used in a multi-point calibration method for the depth of a horizontal directional drilling guiding instrument in accordance with a preferred embodiment of the present invention.

**DETAILED DESCRIPTION OF THE PREFERRED
EMBODIMENTS**

20 A multi-point calibration method for the depth of a horizontal directional drilling guiding instrument in accordance with the present invention comprises the steps of:

(1) maintaining a constant power output of a normal power transmitter in a specific power supply condition;

(2) selecting two depth calibrations;

(3) receiving signals including a signal s at the position of the transmitter and two signals at two depth calibration points with intensities of s_1 , s_2 respectively by the receiving instrument, wherein the default value of the distance of the first calibration point s_1 from the transmitter is equal to 3 meters, and the default value of the distance of the second calibration point s_2 from the transmitter is equal to 10 meters, provided that two-point calibration is adopted;

(4) performing a signal shaping and an analog/digital conversion to the signals s , s_1 , s_2 received by the receiving instrument (as shown in FIGS. 1); and

(5) entering the signal s , s_1 , s_2 into a central digital signal processor after the analog/digital conversion takes place, and performing a depth calibration by a linear compensation method to obtain a required measured depth, wherein the central digital signal processor performs a calculation according to the equation of:

$$r = (M_0/s)^{1/3} + [(M_0/s)^{1/3} - 5] \times k$$

where, r is the measuring depth, and M_0 is the measured value, and s is the intensity k of the signal transmitted from the transmitter and received by the receiving instrument, and the value of k is obtained by the equation of:

$$k = [10 - (M_0/s_2)^{1/3}] / [(M_0/s_2)^{1/3} - 5]$$

where, M_0 is the measured value, and s_2 is the intensity of a signal occurred at the second calibration point and received by the receiving instrument, and the measured value M_0 is calculated by the equation of:

$$M_0 = s_1 \times R^3$$

where, s_1 is the intensity of a signal occurred at the first calibration point and received by the receiving instrument, and R is the distance of the first calibration point from the transmitter and has a default value of 3 m.

What is claimed is:

1. A multi-point calibration method for the depth of a horizontal directional drilling guiding instrument, comprising the steps of:

(1) maintaining a constant power output of a power transmitter in a specific power supply condition;

(2) selecting at least two depth calibrations;

3

- (3) receiving a signal transmitted from a transmitter and an intensity of a signal at a depth calibration position by a receiving instrument;
- (4) performing a signal shaping and an analog/digital conversion to the signal received by a signal receiving instrument; and
- (5) entering the signal into a central digital signal processor, and performing a depth calibration by any compensation method to obtain a required measuring depth; wherein the compensation method includes a linear compensation method, the linear compensation method is implemented by the equation of:

$$r = (M_0/s)^{1/3} + [(M_0/s)^{1/3} - 5] \times k$$

where, r is the measuring depth, and M_0 is the measured value, and s is the intensity k of the signal transmitted from the transmitter and received by the receiving instrument, and the value of k is obtained by the equation of:

$$k = [10 - (M_0/s_2)^{1/3}] / [(M_0/s_2)^{1/3} - 5]$$

where, M_0 is the measured value, and s_2 is the intensity of a signal occurred at the second calibration point and received by the receiving instrument.

20

4

- 2. The multi-point calibration method for the depth of a horizontal directional drilling guiding instrument as recited in claim 1, wherein the calibration points includes a first calibration point s_1 and a second calibration point s_2 used for carrying out a compensation method.

- 3. The multi-point calibration method for the depth of a horizontal directional drilling guiding instrument as recited in claim 1, wherein the measured value M_0 is calculated by the equation of:

$$M_0 = s_1 \times R^3$$

where, s_1 is the intensity of a signal occurred at the first calibration point and received by the receiving instrument, and R is the distance of the transmitter from the first calibration point.

- 4. The multi-point calibration method for the depth of a horizontal directional drilling guiding instrument as recited in claim 2, wherein the compensation method includes a linear compensation method.
